UNITED STATES PATENT OFFICE

144,254

DESIGN FOR A WASHER CONTROL PANEL OR SIMILAR ARTICLE

Hercheal Wood Miller, Davenport, Iowa, assignor
to American Machine and Metals, Inc., New
York, N. Y., a corporation of Delaware

Application July 14, 1945, Serial No. 120,720

Term of patent 14 years

(Cl. D26—1)

To all whom it may concern:

Be it known that I, Hercheal Wood Miller, a citizen of the United States and a resident of Davenport, in the county of Scott and State of Iowa, have invented a new, original, and ornamental Design for a Washer Control Panel or Similar Article, of which the following is a specification, reference being had to the accompanying drawing, forming part thereof.

Figure 1 is a plan view of a washer control panel or similar article showing my new design.

Figure 2 is a side elevational view thereof.

Figure 3 is a front elevational view thereof.

I claim:

The ornamental design for a washer control panel or similar article, as shown.

HERCHEAL WOOD MILLER.
